(57) **CLAIM**

The ornamental design for a housing for a storage device, as shown.

DESCRIPTION

FIG. 1 is a front, right and top perspective view of a housing for a storage device showing our new design;

FIG. 2 is a top plan view thereof;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a bottom plan view thereof; and,

FIG. 8 is a sectional view thereof, taken along line 8—8 of FIG. 2.
